UNITED STATES PATENT OFFICE.

GERTRUDE CAMPBELL, OF CHICAGO, ILLINOIS.

MONTHLY-PROTECTOR.

SPECIFICATION forming part of Letters Patent No. 276,770, dated May 1, 1883.

Application filed December 30, 1882. (Model.)

To all whom it may concern:

Be it known that I, GERTRUDE CAMPBELL, a citizen of the United States, residing at Chicago, in the county of Cook and State of Illinois, have invented a new and useful Improvement in Monthly-Protectors, of which the following is a specification.

My invention relates to improvements in monthly-protectors, which are made water-proof to keep the undergarments from being soiled, and at the same time are made of such thin and flexible material as not to be uncomfortable to the wearer, and of suitable shape to retain liquids or to retain cloths as absorbers. I attain these results by the construction and general shape shown in the accompanying drawings, in which—

Figure 1 is an elevation and longitudinal vertical section of the protector. Fig. 2 is a plan view, and Fig. 3 is a cross-section at the opening.

a represents the waistband, which is buckled around the waist, and from which the protector *g* is suspended by the straps *d* and buckle *b*.

e is the opening for the passage of liquids, and through which cloths and suitable absorbers are laid into the protector *g* until it is desirable to replace them.

The protector *g* is made out of very thin water-proof material, and hence it is also very flexible and not as uncomfortable to the limbs, between which it is worn, as some others which may or may not be patented, but are practically a stiff U-shaped section of thick

rubber and extremely uncomfortable. As the 35 wearer is seated any liquid contained in the absorbers may be squeezed into the ends *e'* or *e*, and still be kept from the underclothing by the water-proof qualities of the bag or protector *g*.

In Fig. 3, *f* and *f'* show how the protector 40 bulges out sidewise, forming a larger space, capacity, or area, in which absorbers lie, than the opening *c* itself, thus keeping the absorbers in their proper place. This shape, as shown in the drawings, forms the improvement for which Letters Patent are asked, the crescent shape, as shown in Fig. 1, the space *e e'*, and the opening into it, *c*, of smaller dimensions.

The radical difference between U shape or 50 cup shape sections and the two sections shown in Figs. 1 and 3 must be very apparent. In other words, the area or space below the opening *c* is partially covered, and also several times larger than the opening itself. This is 55 found to be a very necessary item, and hence deemed worthy of Letters Patent.

I claim the same as follows:

The soft-rubber (or other water-proof material) inclosing-sack furnished with two straps 60 at one end and one at the other, and with a central longitudinal opening cut out from the rubber for insertion of the ordinary napkin, all as and for the purpose described.

GERTRUDE CAMPBELL.
